UNITED STATES PATENT OFFICE.

JULIUS S. MEYER, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 1⁷ 547, dated January 15, 1884.

Application filed July 29, 1883. Term of patent 3½ years.

To all whom it may concern:

Be it known that I, JULIUS S. MEYER, of New York, N. Y., have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

The ground *a* is loosely filled in by a system of variegated small geometric work. Over this ground are disposed four large flower-and-leaf groups. *A* has a central mass of geranium-leaves and small flowers with ferns projecting below and blossom-and-leaf sprays above. *B* has a central mass of open flowers and leaves, with projecting fern and blossom sprays and

a scattered trailing leaf-spray below. *C* has two large open flowers on a mass of leaves and small projecting sprays. *D* has two large geranium-leaves above a mass of small flowers and leaves, and projecting fern and leaf sprays.

I claim—

1. The design for a carpet, consisting of the group *A*, substantially as shown and described. 30
2. The design for a carpet, consisting of the group *C*, substantially as shown and described.
3. The design for a carpet, consisting of the group *C*, substantially as shown and described.
4. The design for a carpet, consisting of the group *D*, substantially as shown and described. 35
5. The design for a carpet, consisting of the groups *A*, *B*, *C*, and *D* and the ground *a*, substantially as shown and described.

JULIUS S. MEYER.
